SPECTACLES

Luc André Marcel Tagnon, Paris, France, assignor to
Societe des Lunetiers, Paris, France

Filed Apr. 19, 1971, Ser. No. 135,514

Claims priority, application France Nov. 6, 1970

Term of patent 14 years

Int. Cl. D16—06

U.S. Cl. D57—1

Fig.1.

Fig. 2.

Fig. 3.

Fig. 4.

Fig.5.

FIG. 1 is a perspective view of spectacles showing my new design.

FIG. 2 is a front elevational view thereof.

FIG. 3 is a side elevational view thereof.

FIG. 4 is a rear elevational view thereof.

FIG. 5 is a top plan view thereof.

The characteristic features of my design reside in the configuration of the L-shaped hinge members and the top front bar including the bridge.

I claim:

The ornamental design for spectacles, substantially as shown and described.
